RELIGIOUS BRACELET

Adolph Frankenthaler, 243 West End Ave.,
New York, N.Y. 10023

Filed Jan. 3, 1967, Ser. No. 5,268

Term of patent 7 years

(Cl. D45—4)

FIG. 1 is a perspective view of a religious bracelet showing my new design;

FIG. 2 is a developed plan view thereof; and

FIG. 3 is a cross-sectional view taken on the line 3—3 of FIG. 2.

I claim:

The ornamental design for a religious bracelet, substantially as shown.
